UNITED STATES PATENT OFFICE.

THOMAS D. MILLEA, OF SPRINGFIELD, MASSACHUSETTS, ASSIGNOR TO SPRINGFIELD ENGINE STOP COMPANY, OF NEW YORK, N. Y., A CORPORATION OF MAINE.

SHUT-OFF DEVICE FOR MOTORS.

SPECIFICATION forming part of Letters Patent No. 702,109, dated June 10, 1902.

Application filed July 31, 1900. Serial No. 25,438. (No model.)

To all whom it may concern:

Be it known that I, THOMAS D. MILLEA, a citizen of the United States of America, residing at No. 36 Keith street, Springfield, in 5 the county of Hampden and State of Massachusetts, have invented new and useful Improvements in Shut-Off Devices for Motors, of which the following is a specification, reference being had to the accompanying drawings and letters of reference marked thereon.

The object of my invention is to provide a device by which a steam-engine or other motor may have the source of supply or energy quickly cut off, so as to check its motion, and 15 a device which may be operated from a point remote from the motor.

My object is further to provide a mechanism by which while the primary motive power for driving the motor is steam and the pressure of steam is employed to operate the shut-off mechanism, yet the force acting directly upon the shut-off mechanism may be derived from air or gas or a liquid other than steam.

My object is further to provide mechanism 25 having the advantages herein set forth.

I accomplish the objects of my invention by the construction herein shown.

In the accompanying drawings, in which like letters of reference indicate like parts, 30 Figure 1 shows a portion of the ordinary type of Corliss engine with so much of my device in operative connection therewith as is required to clearly explain the construction and operation. Fig. 2 is a detached view of 35 a spring device to be substituted for the fluid device, if desired. Fig. 3 is a view of my improved packing-ring.

In detail, *a* indicates an electrically-operative mechanism adapted to cause a valve to 40 be opened or a spring to be released; *b*, reach-rods; *c*, wrist-plate; *d*, eccentric-rod; *e*, bell-crank lever; *f*, grab-hook; *g*, grab-hook spring; *h*, valve-bonnet; *i*, cut-out cam; *j*, valve-toe; *k*, rod to dash-pot; *l*, dash-pot; *m*, 45 exhaust-valve arm; *n*, connecting-rods between cut-off cams and device to operate the same; *o*, cylinder; *p*, piston-rod; *r*, reservoir; *s*, conduit from reservoir to shut-off cylinder; *t*, electrically-operated valve; *u*, conduit from 50 steam or other supply to reservoir; *v*, relief

conduit; *w*, connecting-rods from wrist-plate to valve-arms.

The construction of my device will be readily understood on reference to the drawings in connection herewith. The shut-off cylinder is located at a convenient point, from which rods extend to the cams *i*, which cams when thrown upwardly engage pins *f'* or other projection on the grab-hooks *f* and throw them out of or prevent their engagement with the valve-toes *j*, thus preventing the further inlet of steam into the cylinders, and hence stopping the engine.

For a mechanism to operate the shut-off rods *n* I prefer to employ a shut-off cylinder provided with a piston and piston-rod and a suitable conduit extending to the cylinder, entering the same at a point below the piston. A reservoir *r* is arranged at some convenient point, having an outlet-conduit *s* 65 and an inlet-conduit *u*, the latter extending to the source of steam-supply or being connected with the steam-supply pipe at some convenient point. The reservoir *r* is filled or substantially filled with water, the result 70 of condensation. An electrically-operative valve device *a* is arranged in the conduit leading from the reservoir to the shut-off cylinder. Suitable electric conductors extend from said valve device to various stations 75 or points in the building, as desired, and a source of electrical energy is provided, so that when contact is made the circuit is completed. The electrically-operating valve device is operated and the valve thereby opened, 80 allowing the water to flow from the reservoir to the shut-off cylinder, being forced thereto by the pressure of steam operating through the inlet-conduit *u*, resulting in forcing the piston in the shut-off cylinder upwardly, 85 and thereby operating upon the grab-hooks through the shut-off rods *n*. One such station or point above referred to is represented by the push-button *z*, from which the conductors or wires *y* extend to the battery *x* and 90 the electric device *a*. Any number of these push-buttons or other suitable circuit-closers may be employed for operating my device from a distance. While I prefer this mechanism or form of construction, it will readily 95

be seen that a spring may be employed in the cylinder and the electrically-operated mechanism be arranged to set the spring free instead of to open a valve to bring about the 5 same result or effect.

In Fig. 2 I show a spring-provided piston in the cylinder which is adapted to be released when the electrically-operating mechanism is energized for the purpose of operating the 10 rods, which throw the grab-hooks out of engagement in the manner hereinbefore described.

As a packing for the piston-head I employ a cup-shaped flexible piece, preferably of rubber, formed as shown in Fig. 3. With this 15 form of packing the pressure in the cylinder under the cup tends to force it outwardly against the wall of the cylinder, and thus pack the same tightly; but when the pressure 20 is removed the cup contracts slightly and the piston will move with the utmost freedom.

Having therefore described my invention, what I claim, and desire to secure by Letters Patent, is—

25 1. The combination of an engine of the "Corliss" type, with cams arranged to throw out the grab-hooks, rods extending from the cams to a device adapted to force said rods upwardly, an electrically-operated mechanism arranged to cause the rod-forcing device 30 to act, suitable electrical conductors, one or more stations or switches, and a source of electrical energy, substantially as shown.

2. The combination of an engine provided with grab-hooks and cut-out cams adapted 35 to throw said grab-hooks out of engagement, with a shut-off cylinder having a piston and piston-rod operatively connected with said cut-out cams, a conduit leading to a source of pressure, and an electrically-operated valve 40 in said conduit, substantially as shown.

3. The combination of a reservoir, with a motor, shut-off mechanism comprising grab-hooks and cut-out cams adapted to throw said grab-hooks out of engagement, in operative 45 connection with a cylinder and a piston therein, a conduit from said reservoir to said cylinder, a valve in said conduit, means to operate said valve, and a conduit from a source of pressure as steam, air, gas, or water, to the 50 reservoir, substantially as shown.

4. The combination of a source of pressure-supply, with a reservoir, a conduit between the two, a cylinder having a piston and a piston-rod, a conduit from said reservoir to said 55 cylinder, an electrically-controlled valve in the last-mentioned conduit, grab-hooks for a motor, cut-out cams adapted to throw said grab-hooks out of engagement, and rod connections between said cut-out cams and said 60 piston-rod, substantially as shown.

THOMAS D. MILLEA.
